UNITED STATES PATENT OFFICE.

ALBERT J. LINDEMANN, OF MILWAUKEE, WISCONSIN, ASSIGNEE TO A. J. LINDEMANN
& HOVERSON CO., OF MILWAUKEE, WISCONSIN.

COOKING-STOVE.

1,127,652.

Specification of Letters Patent.

Patented Feb. 9, 1915.

Application filed May 2, 1914. Serial No. 835,829.

To all whom it may concern:

Be it known that I, ALBERT J. LINDEMANN, a citizen of the United States, and resident of Milwaukee, in the county of Milwaukee and State of Wisconsin, have invented certain new and useful Improvements in Cooking-Stoves; and I do hereby declare that the following is a full, clear, and exact description thereof.

10 My invention relates to combined solid fuel and gas burning stoves designed for baking and over fire cooking, its object being to economically provide simple, compact, seam-tight and efficient stoves of the 15 kind stated, each constructed to permit the use of either solid or gas fuel without necessitating the removal or replacement of any of its parts, and in which both kinds of said fuel may be utilized at the same time; 20 a novel flue system of the stove serving for ample draft for the combustion of the solid fuel, gas or both, as well as to economize space for chambers in which are located the gas burners for oven heating and 25 over fire cooking, said flue system being such that none of the products of combustion of the solid fuel can enter said chambers.

In view of the foregoing my invention 30 consists in structural peculiarities of the combined solid fuel and gas burning stove herein particularly set forth with reference to the accompanying drawings and pointed out in the claims of this specification.

35 Figure 1 of the drawings represents a vertical longitudinal sectional view of a combined solid fuel and gas burning stove in accordance with my invention, the section being indicated by line 1—1 in Figs. 2 and

40 Fig. 3; Fig. 2, a cross-section of the stove indicated by line 2—2 in Figs. 1 and 3, parts being broken away; Fig. 3, a horizontal section of said stove indicated by line 3—3 in Fig. 1; Fig. 4, a sectional view indicated by 45 line 4—4 in Figs. 3 and 5, and illustrating a chamber containing an oven heating gas-burner; Fig. 5, a horizontal section indicated by line 5—5 in Fig. 4; Fig. 6, a view similar to Fig. 4, omitting the gas-burner

50 and illustrating a combined vertically adjustable damper and deflector element of said chamber in elevated position, and Fig. 7, a horizontal section indicated by line 7—7 in Fig. 6.

55 Referring by numerals to the drawings, 8

indicates the base, 9 and 9' the bottom, 10 the end walls, 11 the side-walls and 12 the top frame of an angular combined solid fuel and gas burning stove in which my improvements are embodied. The major portion 9 60 of the bottom is preferably sheet-steel, and the remainder 9' of said bottom is a somewhat elevated cast-metal housing adjacent to one corner of the stove-body. Each of the walls 10 and 11 of the stove preferably 65 comprises a pair of parallel steel sheets at a suitable interval apart, and interposed insulation 13 of asbestos or other suitable material. There is preferably insulated seam-joining of the sheet-metal of the bottom and 70 walls of the stove, and a continuous depending flange of the top frame of said stove is riveted in between the metal sheets of said walls, all as shown in Figs. 1 and 2, this construction being designed to provide 75 joints that remain air-tight, regardless of expansion and contraction of the stove-body.

Arranged in the stove, and for the most part parallel to an end wall of the same, is 80 a partition 14 between the side walls of said stove, said partition being preferably of sheet steel having flanges thereof riveted to said side walls. The partition is shown as forming an end wall of a bake-oven 85 provided in the stove, and it is offset below the bottom 15 of the oven toward the adjacent end wall of the stove-body to increase the area of flue-space hereinafter more particularly specified. The height of the partition 90 is less than the distance between the bottom and top of the stove-body and its upper end corners with the top 16 of said bake-oven.

Detachably supported in connection with brackets 17 in the space between the partition 14 and the adjacent end wall of the stove, is a fire-box 18 provided with a grate for the support of solid fuel, the grate shown being one having shaking-members 19. Within the space below the fire-pot it is 100 intended to arrange a removable receptacle for the reception of ashes from the solid fuel, such a receptacle being indicated by dotted lines in Fig. 1, and in practice a front doorway and door for said space is 105 provided.

A portion of the oven-top 16 is depressed as shown at 16' under a curvilinear portion 20' of an otherwise horizontal plate 20 that constitutes the bottom of a chamber in which 110

to isolate gas-burners 21, under a grating 22 forming part of the stove top, over fire heating and cooking being done in receptacles set on the grating over the gas-burners. The bottom curve of said chamber is conveniently provided with a guide 23 for a trash slide 24 under said gas-burners, and the chamber bottom has a depending flange riveted in between the metal sheets of the 10 adjacent end wall of the stove for the purpose stated in the foregoing with reference to a flange of the top frame of the stove.

The top of the stove over the horizontal portion of the oven therein is shown as comprising two cast-metal plates 25, 26 having interlocking engagement and supported on ledges with which the top frame 12 and chamber-bottom 20, 20' are provided. Each of the plates 25 and 26 have countersunk 20 cooking holes therein for the engagement of flush-fit covers, such stove holes and covers being common in solid fuel burning cooking stoves on which over fire heating and cooking is done in various receptacles.

25 The end wall 27 of the bake-oven is provided with a series of upper apertures 28 opening into a flue 29 of sheet metal or otherwise having flanges thereof riveted to said oven, the vertical wall of the flue being provided at its lower end with outlet ports in register with ports of a circular plate 30 riveted to said wall. Pivotaly centered on the plate 30 is a rotatably adjustable damper 31 for the ports aforesaid, 30 the preferred means for actuating the damper being hereinafter specified. If preferred, a sliding damper may be employed.

The bottom 15 of the bake-oven is immediately above the lower offset 14' of its end 40 wall 14 constituting the partition aforesaid, and extending within the space between the oven bottom and the bottom of the stove as a whole is a cast-metal preferably cylindrical solid bottom pot 33 constituting a chamber in which to isolate a gas-burner 34. The lower portion of the wall of the pot, below the stove bottom, is provided with air-inlet ports, and a damper 35 for these inlets is provided with upper vertical arms 35' for 50 which said pot is formed with guide offsets 33', 33''. The pot is provided with upper and lower outer horizontal flanges, and these flanges are riveted in connection with the oven and stove bottoms. The upper flange 55 of the pot fits within a step of a depression of the oven bottom flush with another step of said depression for the engagement of a deflector-plate 36 attached to the arms 35' of the damper 35, said plate being flush with 60 said oven bottom when in lowered position.

The links 37 and 38 of toggles are respectively connected to the damper 35 and to a tumbling-rod 39, 39', which rod extends through the offsets 33'' of the pot 33 and 65 through an end wall of the stove under the

housing portion 9' of the stove bottom, the outer end of said rod being provided with a preferably indexed crank 40. Fast on the tumbling-rod under the housing 9' is a lever 41, and coupled to the lever is a pitman 42 70 wristed to the damper 31 above specified, whereby when said tumbling-rod is actuated to elevate the damper 35 and deflector plate 36, the flue 29 is opened to permit circulation of air through the oven, which oven is 75 heated from within by ignited gas emanating from the burner 34. The housing 9' is provided with a guide-boss 9'' for the pitman 42, as shown in Fig. 2, and a bearing 43 for the tumbling-rod is suspended from 80 the stove bottom, as shown in Fig. 3.

The bottom of the pot 33 is notched to provide clearance for the gas-pipe 44 in connection with the burner 34, and the damper and plate connecting arms 35' are of such 85 number and disposition as to insure easy vertical adjustment of said damper and plate. There is close fit of the pot-bottom on said gas-pipe.

The pot 33 constitutes a ventilating chamber when open, and when closed, the confined heated air therein prevents chilling of the deflector plate 36 that is then a portion of the oven bottom.

From the foregoing it will be understood 95 that there is flue-space extending over the top of the oven then downward and under said oven. This flue-space is open above and below said oven to a back-flue 45 of the stove, said back-flue being of any suitable 100 construction and adapted for connection with stovepipe 45' leading to a chimney. The upper opening from the flue-space in the stove to the back-flue is controlled by a swing-damper 46 fast on an outwardly 105 extending operating rod 47 for which bearings are provided in said flue, one of the bearings 48 being shown in Fig. 2, and the operator end of the rod is conveniently located. The flue-damper being open, the 110 products of combustion of solid fuel burning in the fire-box 18 have direct outlet to the back-flue 45, but said damper being closed, said products of combustion travel 115 in said flue-space toward the lower opening therefrom to said back-flue, whereby the oven is heated for baking.

In the flue-space under the oven is a baffle-plate 49 (shown in Fig. 3) extending from the pot 33 to the back wall of the stove 120 and to the right of the lower opening from said space to the back-flue, whereby the products of combustion of solid fuel as aforesaid are deflected around said pot on their way to outlet.

Because of the centering of the gas-burner 34 under the oven, the pot 33 inclosing said burner is nearer the offset 14' of the partition 14 than the opposite end wall of the stove, and to prevent congestion of 125

products of combustion in the narrowest portion of the flue-space aforesaid, the stove bottom is there provided with depressions 50 and 51, the area of these depressions being sufficient to equalize the cubic inches of said flue-space all around said pot.

When only solid fuel is used in the stove, the crank 40 is preferably turned to lower the combined pot-damper 35 and deflector-plate 36, as well as to adjust the damper 31 to a position that cuts off the oven-flue 29 from the main flue-space aforesaid, and to indicate the adjustment of said dampers and deflector plate, the index word "Coal" 15 is shown on the then uppermost side of said crank. The word "Gas" may be provided on the reverse side of the crank 40 to index a reverse position of the dampers 31, 35 and the deflector-plate 36, when the oven is to 20 be heated by means of gas utilized through the burner 34, or when gas is burned to supplement the heating of said oven by products of combustion of solid fuel circulated in the main flue space.

It is not absolutely essential that the outlet ports of the oven-flue be closed when solid fuel alone is burned in the stove, as the draft in the main-flue space will be sufficient to prevent said products of combustion finding their way through said flue into the oven. Neither is it absolutely essential that provision be had for closing the air inlets to the pot 33 when the deflector plate 36 is lowered.

The deflector-plate 36 having been lifted and the gas-burner 34 lighted, the heated air is diverted toward the sides of the oven in which it rises to be drawn out through the upper apertures of the same into the flue 29 and from thence into the main flue space open at the bottom to the uptake back-flue of the stove, said heated air passing under the bottom of said oven where it is again utilized for oven-heating, this being an advantageous economic feature in the use of the stove. The bottom of the pot being closed immediately below the air-inlets to said pot, it insures a steady upward current of air under suction created by the combustion of gas at the burner 34, whereby downward deflection of heat is avoided, and the area of said inlets is such that sufficient air is admitted to the pot to insure perfect combustion of the ignited gas.

The oven is provided with the usual brackets 52 for the support of shelves 53, and a drop-door for the oven is shown in Fig. 2. The piping 54 herein shown is that of the stove to which the gas-burners 21 are connected.

It is to be noted that the recessing of the oven bottom 15 is such as to provide for the nesting thereon of considerable surface of the deflector plate 36, whereby said plate 65 in lowered position is readily heated to the

same degree of temperature as said oven-bottom.

I claim:

1. A combined solid fuel and gas-burning stove having an oven therein, a gas-burner chamber extending vertically across flue space between the oven and stove bottoms, a plate that seats in said oven bottom to cover said chamber, and lifting-mechanism for the plate, said plate serving as a deflector when in lifted position.

2. A combined solid fuel and gas burning stove having an oven, a damper controlling an oven-outlet to main flue-space in the stove, a gas-burner chamber depending from the bottom of the oven, a vertically adjustable deflecting plate constituting a cover for said chamber when lowered, and means by which to effect simultaneous adjustment of said damper and plate, the damper being moved to open said oven outlet when the plate is elevated.

3. A combined solid fuel and gas burning stove having an oven provided with a vertical flue upwardly open thereto, a damper controlling a lower outlet of the flue to main flue space in the stove, a gas-burner chamber depending from the bottom of said oven, a vertically adjustable deflecting plate constituting a cover for said chamber when lowered, and means by which to effect simultaneous adjustment of said damper and plate, the damper being moved to open said flue when the plate is elevated.

4. A combined solid fuel and gas burning stove having an oven, a gas burner chamber depending from the oven bottom and provided with lower end air-inlets, a vertically adjustable damper for said air-inlets, a deflecting plate movable with the damper, the plate constituting a cover for said chamber when lowered; and means for adjusting said connected damper and plate.

5. A combined solid fuel and gas burning stove having an oven, a damper controlling an oven outlet to main flue-space in the stove, a gas-burner chamber depending from the oven bottom and provided with lower end air inlets, a vertically adjustable damper for said air-inlets and a deflecting plate movable therewith, the plate constituting a cover for said chamber when lowered; and means by which to effect a simultaneous adjustment of said dampers and plate, both dampers being in open position when the plate is elevated.

6. A combined solid fuel and gas burning stove having an oven, a damper controlling an oven outlet to main flue-space in the stove, a gas-burner chamber depending from the oven bottom and provided with lower end air inlets, a vertically adjustable damper for said air-inlets and a deflecting plate movable therewith, the plate constituting a cover for said chamber when lowered; a

tumbling-rod in toggle union with the chamber-damper, a lever rigid with the rod, and a pitman connecting the lever and the damper first aforesaid.

5 7. A combined solid fuel and gas burning stove having an oven, a damper controlling an oven outlet to main flue-space in the stove, a gas-burner chamber depending from the oven bottom and provided with lower 10 end air inlets, a vertically adjustable damper for said air-inlets and a deflecting plate movable therewith, the plate constituting a cover for said chamber when lowered; a tumbling-rod in toggle union with the chamber-damper, a lever rigid with the rod, a pitman connecting the lever and the damper first aforesaid, and an index-crank fast 15 on an exposed portion of said rod.

8. A combined solid fuel and gas burning stove having an oven provided with a vertical flue upwardly open thereto, a damper controlling a lower outlet of the flue to main flue space in the stove, a gas-burner chamber depending from the oven bottom 20 and provided with lower end air inlets, a vertically adjustable damper for said air-inlets and a deflecting plate movable therewith, the plate constituting a cover for said chamber when lowered; and means by which 25 to effect a simultaneous adjustment of said dampers and plate, both dampers being in open position when the plate is elevated.

9. A combined solid fuel and gas burning stove having an oven provided with a vertical flue upwardly open thereto, a damper controlling a lower outlet of the flue to main flue space in the stove, a gas-burner chamber depending from the oven bottom and provided with lower end air inlets, a vertically adjustable 30 damper for said air-inlets and a deflecting plate movable therewith, the plate constituting a cover for said chamber when lowered; a tumbling-rod in toggle union with the chamber-damper, a lever rigid with the rod, and a pitman connecting the lever 35 and the aforesaid flue-damper.

10. A combined solid fuel and gas burning stove having an oven provided with a vertical flue upwardly open thereto, a damper 40 controlling a lower outlet of the flue to main flue space in the stove, a gas-burner chamber depending from the oven bottom and provided with lower end air inlets, a vertically adjustable damper for said air-inlets and a deflecting plate movable therewith, the plate constituting a cover for said chamber when lowered; a tumbling-rod in toggle union with the chamber-damper, a lever rigid with the rod, a pitman connecting 45 the lever and the aforesaid flue-damper, and an indexed crank on the outer end of said rod.

11. A combined solid fuel and gas burning stove having an oven, a gas-burner chamber depending from the bottom of the 50

oven and provided with guides, a vertically adjustable deflecting plate surmounting arms engaging said guides and constituting a cover for said chamber when lowered, and means for adjusting the plate.

12. A combined solid fuel and gas burning stove having an oven, a gas burner central of the oven below the same, a chamber in the form of a pot inclosing the burner, the air inlets to the pot being under the 70 stove bottom and said pot provided with guide offsets; a vertically adjustable damper for said air-inlets provided with arms engaging said guide-offsets of the pot, a deflecting-plate in connection with said arms 75 and which seats in the oven bottom to constitute a pot-cover when lowered, and means for adjusting the connected damper and deflecting plate.

13. A solid fuel and gas burning stove 80 having an upper gas-burner isolating chamber the bottom of which is a partly horizontal and partly curvilinear solid plate fashioned at the upper extremity of its curve to form a ledge upon which to rest a removable top-plate of the stove, whereby 90 the plate first aforesaid constitutes a supplementary part of the top-frame of said stove.

14. A solid fuel and gas burning stove 95 having an upper gas-burner isolating chamber, the bottom of which is a partly horizontal and partly curvilinear solid plate in air-tight union with a wall of the stove and fashioned at the upper extremity of its 100 curve to form a ledge upon which to rest a removable top-plate of the stove, whereby the plate first aforesaid constitutes a supplementary part of the top-frame of said stove.

15. A solid fuel and gas burning stove having an upper gas-burner isolating chamber the bottom of which is a partly horizontal and partly curvilinear solid plate fashioned at the upper extremity of its curve 110 to form a ledge upon which to rest a removable top-plate of the stove and which has said curve provided with a trash-pan 115 guide, the plate first aforesaid constituting a supplementary part of the top-frame of said stove.

16. A combined solid fuel and gas burning stove having an oven, a gas-burner chamber having an upper outer flange thereof seated in a step of a depression of the oven-bottom flush with another step of said depression, a plate that seats in the upper step of the aforesaid depression to cover said chamber and be flush with said oven bottom, and lifting mechanism for the plate, 120 said plate serving as a deflector when in lifted position.

17. A stove having an oven, a gas-burner chamber depending from the oven and provided with lower air inlets, a damper for 125 130

- said inlets, a vertically adjustable deflecting plate constituting a cover for said chamber when lowered, a damper controlling escape of heat from the oven, and means by which 5 to simultaneously adjust the plate and dampers with reference to circulation or non-circulation of heat in said oven.
18. A stove having an oven, a gas-burner chamber depending from the oven and provided with lower air inlets, a damper for 10 said inlets, a vertically adjustable deflecting-plate constituting a cover for said chamber when lowered, and means by which to simultaneously adjust the plate and dampers with reference to circulation or non-circulation of heat in said oven.
19. A combined solid fuel and gas burning stove having an oven, a gas-burner chamber having communication with the 20 oven through the bottom of the same, a movable plate in the oven over the chamber, and raising and lowering mechanism connected to the plate, said plate in raised position serving as a deflector for gas-fire 25 and in lowered position as a closure for the upper end of said chamber to adapt the oven for baking when solid fuel is used in the stove.
20. A combined solid fuel and gas burning stove having an oven, a gas-burner chamber having communication with the oven through the bottom of the same, a movable plate in the oven over the chamber, and plate raising and lowering mechanism under control outside of the stove, 35 said plate in raised position serving as a deflector for gas-fire and in lowered position as a closure for the upper end of said chamber to adapt the oven for baking when solid fuel is used in the stove.
21. A combined solid fuel and gas burning stove having an oven, an air-chamber crossing flue-space in the stove under the oven, a burner in the chamber, a gas-pipe 45 connected to the burner, a movable cover for said chamber, and cover raising and lowering mechanism under control outside of the stove, said cover in raised position serving as a deflector in said oven for products of combustion from the underlying 50 burner.
22. A combined solid fuel and gas-burning stove having an oven and a gas-burner chamber crossing flue-space in the stove 55 under the oven, the chamber being closed at the bottom and provided with an air-inlet or inlets at its lower end, a movable plate in the oven over the chamber, and raising and lowering mechanism connected to the 60 plate, said plate in raised position serving as a gas-fire deflector and in lowered position as a closure for the upper end of the aforesaid chamber.
23. A combined solid fuel and gas burning stove having an oven, a gas-burner 65 chamber depending from the bottom of the oven across flue-space in the stove, a movable support, means for vertically adjusting the support, and a plate in connection with the support to be raised and lowered in 70 said oven, the plate in raised position serving as a gas-fire deflector and in lowered position as a cover for said chamber.
24. A combined solid fuel and gas burning stove having an oven, a gas-burner 75 chamber depending from the bottom of the oven across flue-space in the stove, a movable support, an actuating rod in connection with the support, and a plate also in connection with said support to be raised and 80 lowered in said oven, the plate in raised position serving as a gas-fire deflector and in lowered position as a cover for said chamber.
25. A combined solid fuel and gas burning stove having an oven, a gas-burner 85 chamber having communication with the oven, a movable plate in the oven, and mechanism in connection with the plate by which said plate is made to serve as a gas- 90 fire deflector in one position of its adjustment and as a closure for said chamber in another position of its adjustment.
26. A stove which is convertible for solid and fluid fuel, comprising an oven, a fire 95 pot, flues for conducting the products of combustion from such fire pot under and around said oven, a burner for fluid fuel located beneath said oven, the floor of said oven being provided with an opening above 100 said fluid fuel burner for admitting flames therefrom into the oven, and a combined valve and baffle plate for controlling said opening, said valve and baffle plate being movable above and either toward or from 105 the upper end of said opening to close or open it.
27. A stove which is convertible for solid and fluid fuel, comprising an oven, a fire 110 pot, flues for conducting the products of combustion from such fire pot under and around said oven, a burner for fluid fuel located beneath said oven, the floor of said oven being provided with an opening above said fluid burner for admitting flames 115 therefrom into the oven, and a combined valve and baffle plate for controlling said opening.
- In testimony that I claim the foregoing I have hereunto set my hand at Milwaukee in 120 the county of Milwaukee and State of Wisconsin in the presence of two witnesses.
- ALBERT J. LINDEMANN.
